F. EDMANDS

BOBBIN

Filed April 18, 1922

Inventor

Frank Edmands

By *Arthur S. Brown*

Attorney

UNITED STATES PATENT OFFICE.

FRANK EDMANDS, OF HOPEDALE, MASSACHUSETTS, ASSIGNOR TO DRAPER CORPORATION, OF HOPEDALE, MASSACHUSETTS, A CORPORATION OF MAINE.

BOBBIN.

Application filed April 18, 1922. Serial No. 554,363.

To all whom it may concern:

Be it known that I, FRANK EDMANDS, a resident of Hopedale, in the county of Worcester and State of Massachusetts, have ⁵ invented an Improved Bobbin, of which the following is a specification.

The present invention is an improvement upon the bobbin shown in the United States Letters Patent of Hastings No. 912,564, ¹⁰ February 16, 1909, and has reference to the way in which the metallic bushing is secured in place within the bobbin.

The improvement is illustrated in the accompanying drawings, wherein—

¹⁵ Figure 1 is a view of the bobbin with its base in section. Fig. 2 is a view showing the base of the bobbin in section and the bushing in elevation. Fig. 3 shows the base of the bobbin and the bushing in longitudinal section in the plane indicated by the line 3—3 in Fig. 2. Figs. 4 and 5 are cross-sections. Fig. 6 is a perspective view of a portion of the periphery of the bushing.

The bobbin A, has an enlarged base B, ²⁰ recessed to receive the encircling rings C, which are adapted to be engaged by holding jaws in a loom shuttle. The interior bore of the bobbin base receives the metal bushing D. Near its outer lower end, the bore in the bobbin base has an inclined annular shoulder E, against which seats a correspondingly shaped outwardly projecting flange F, at the rear end of the bushing D. The bushing is driven into place until the flange F, seats against the shoulder E, thereby insuring the proper longitudinal position of the bushing within the bobbin base. Likewise, the inner end of the bushing is bevelled at G, so as to seat against a correspondingly bevelled shoulder H, of the bobbin bore.

In order to firmly hold the bushing in place so that it cannot be loosened by the pulling of the bobbin from a tightly fitting spindle, the outer peripheral surface of the bushing is so constructed as to securely engage the interior surface of the bobbin bore. At the middle of the bushing there is a peripheral groove I, extending all the way round the exterior of the bobbin, and there is a second outer peripheral groove J, adjoining the outer flange F. The exterior

surface of the bushing between these two grooves, and the exterior surface of the bushing between the groove I, and the inner bevel G, are each equipped with a plurality of incisions K. The incisions extend around the bushing at frequent intervals so that there is a large number of incisions in each encircling row. Each incision extends angularly to the length of the bushing. Each incision is made by indenting the metal of the bushing (usually brass), the result being to produce along one edge a slight outward projection or burr, as indicated at L, in ⁶⁰ Figs. 4 and 6.

The consequence is that when the bushing is driven into the bore of the bobbin the wood of the bobbin is slightly compressed and expands into the grooves I and J, as indicated in Fig. 2 and also into the grooves K, as indicated in Fig. 4. The outwardly extending burrs or projections L, embed themselves in the wood of the bobbin. The result is that the bushing is securely maintained within the bobbin and does not come loose in withdrawing the bobbin from a tightly fitting spindle.

I claim—

1. A bobbin having a metallic bushing ⁸⁰ within its bore, the bore of the bobbin having inner and outer inclined shoulders, and the bushing having a bevelled inner end and an outer inclined flange to fit said shoulders respectively, and the external periphery of the bushing having peripheral grooves and rows of angularly extending incisions, each incision having along one edge an outwardly projecting burr.

2. A bobbin having a metallic bushing ⁹⁰ within its bore, the external periphery of the bushing having peripheral grooves and rows of angularly extending incisions, each incision having along one edge an outwardly projecting burr.

3. A bobbin having a metallic bushing within its bore, the external periphery of the bushing having rows of angularly extending incisions, each incision having along one edge an outwardly projecting burr. ¹⁰⁰

In witness whereof, I have hereunto signed my name.

FRANK EDMANDS.
